UNITED STATES PATENT OFFICE.

LED L. RICHARDSON, OF CLEVELAND, OHIO, ASSIGNOR TO THE CLEVELAND ROCK DRILL COMPANY, OF CLEVELAND, OHIO.

STEEL RETAINER FOR ROCK DRILLS.

Application filed April 14, 1927. Serial No. 183,645.

The present invention is directed to improvements in steel retainers for rock drills of the percussive type.

The primary object of the invention is to provide a device of this character so constructed that the retainer can be held positively in its operative position to prevent accidental disengagement of the drill steel from the drill.

10 Another object of the invention is to provide means whereby one of the side rods of the drill can be utilized as a medium for holding the retainer in place upon the drill.

In the accompanying drawing:—

15 Figure 1 is a side elevation of the front head of a rock drill, partly in section.

Figure 2 is a front view of retainer.

Referring to the drawing, 1 designates the front head of a drill of the percussive type 20 having a drill steel 2 engaged therein and provided with the conventional collar 3.

The front head 1 is held in place on the drill cylinder 3' by side rods 4 as is customary. One of the side rods 4 is threaded, as at 5, 25 as is customary and has an axial socket 6 formed therein. Mounted in the socket 6 is a coil spring 7 and slidable in said socket is a plunger 8 having a reduced extension 9 and resultant annular shoulder 10 and against 30 which the outer end of the spring 7 rests, the extension being confined within the helices of the spring. The spring 7 serves to normally hold the plunger 8 in such position that its outer end will be extended from the 35 socket 6, the purpose of which will be later explained.

Threaded upon the outer end of one of the side rods 4 is a block 11, the forward end of which has formed integral therewith a 40 hook 12 for pivotally coupling the retainer 13 to the drill.

The retainer 13 is formed from a single blank of metal and comprises angularly disposed arms 14 and 15, the former having an 45 eye 16 for pivotally engaging the hook 12. The arms 14 and 15 have formed therein respectively, communicating apertures 17 and 18, the latter being smaller in diameter than the former in order to prevent passage of the 50 collar 3 of the drill steel when the retainer is in its operative position, as shown in full lines in Figure 1. The aperture 18, being relatively large will permit the passage of the collar therethrough when the retainer is in the position 55 as indicated in dotted lines in Figure 1.

In order that the retainer will be maintained positively in its open position regardless of the angular position of the drill the rim of the eye 16 is formed with a flat face 19 adapted to be yieldably engaged by the 60 outer end of the plunger 8. Owing to the presence of the spring 7, the retainer can be swung to its open or closed position with little effort, and when in either position the plunger will maintain the same set. It will 65 be of course understood that when the flat face 19 is fully engaged with the ends of the plunger the holding action will be more positive than when the face 19 is angularly disposed with respect thereto, as shown in 70 dotted lines in Figure 1.

Since the plunger 8 can be forced into the socket 6 the retainer can be conveniently removed from the drill or replaced thereon.

The side rod 4 which carries the block not 75 only performs its function, but serves as means for connecting the retainer to the drill head. From the foregoing it will be observed that the block 11 is used in lieu of one of the usual side rod nuts, there being a pair of 80 springs 20 interposed between the block 11 and front head flange 21 of the drill.

Having thus described the invention, I claim:

1. The combination with the cylinder of a 85 rock drill, of a front head therefor, a drill steel operatively connected with the front head and provided with a collar, side rods for holding the front head and cylinder together, a block upon one of the side rods, a 90 spring pressed plunger slidably contained in said side rod, a drill steel retainer encircling the drill steel in advance of the collar, said retainer being pivotally engaged with the block and yieldably engaged by the 95 plunger.

2. The combination with the cylinder of a 100 rock drill, of a front head, a drill steel operatively connected with the front head and provided with a collar, side rods for holding the front head and cylinder together, a spring pressed plunger slidably in one of the side rods, a block engaged with said side rod and having a hook carried thereby, a drill steel retainer encircling the drill steel in advance 105 of the collar, said retainer having an eye for pivotally engaging the hook, the rim of the eye being yieldably engaged by said plunger, as and for the purpose set forth.

3. The combination with the cylinder of a 110

rock drill, of a front head, a drill steel operatively connected therewith and having a collar, side rods for holding the cylinder and front head together, one of said side rods having a socket therein, a spring pressed plunger in said socket, a block mounted on said side rod, a drill steel retainer encircling the drill steel in advance of the collar, means for pivotally connecting the retainer with the block, said plunger being capable of yieldably engaging the pivotal means for maintaining the retainer in its operative position.

4. The combination with the cylinder of a rock drill, of a front head, side rods for holding the cylinder and front head together, a drill steel operatively connected with the front head and having a collar, a block engaged with one side rod, a drill steel retainer pivotally connected with the block and encircling the drill steel in advance of the col-

lar, and means slidably contained in said side rod for yieldably engaging the retainer to hold the same in its operative position.

5. The combination with the cylinder of a rock drill, of a front head, side rods for holding the cylinder and front head together, a spring pressed plunger slideable in one of the side rods, a block carried by said side rod, a hook carried by the block, a drill steel operatively connected with the front head and having a collar, a drill steel retainer comprising angularly disposed arms having communicating apertures therein for accommodating the drill steel, one of the arms having an eye for pivotally engaging the hook, the rim of the eye having a flat face for engagement with the plunger to yieldably maintain the retainer in its operative position.

In testimony whereof I affix my signature.
LED L. RICHARDSON.
